Patented Nov. 8, 1921.

2 SHEETS—SHEET 2.

UNITED STATES PATENT OFFICE.

JOSEPH O. FULLER, OF PROVIDENCE, RHODE ISLAND.

SPORE-TRAP.

1,396,568.

Specification of Letters Patent.

Patented Nov. 8, 1921.

Application filed August 25, 1921. Serial No. 495,443.

To all whom it may concern:

Be it known that I, JOSEPH O. FULLER, a citizen of the United States, residing at Providence, in the county of Providence and 5 State of Rhode Island, have invented certain new and useful Improvements in Spore-Traps, of which the following is a specification.

My invention relates to a device for automatically exposing sensitized plates to the atmosphere.

It has heretofore been customary to manually expose sensitized plates to the atmosphere for a definite prolonged period at 15 different times during the day in order to determine the relative profusion of spores in the atmosphere during the several periods.

The essential objects of my invention are to automatically expose in succession each 20 of a series of plates for a definite prolonged period; to insure a uniform period of exposure for each plate; to enable the determination of the hour of the day the exposure of any given plate occurred; to shift the 25 succeeding plates instantaneously and completely at the end of each period of exposure in order that the spore record of each period shall be distinct and accurate; to prevent the exposure of more than a single 30 plate at a time; to facilitate the mounting or removal of the plates; to conveniently and portably house the device; and to actuate the carrier by a compact and accurately 35 operating mechanism.

To the above ends essentially my invention relates to such parts and to such combinations of parts as fall within the scope of the appended claims.

In the accompanying drawings which 40 form a part of this specification and which illustrate the principle of this invention in the best mode now known to me of applying that principle,

Figure 1 is a plan view of my trap with 45 the door thrown back,

Fig. 2, a front elevation of the same,

Fig. 3, a plan view of the same with the cover section thrown back,

Figs. 4 and 5, partial sections on lines 50 4-4 and 5-5 respectively of Fig. 1,

Fig. 6, a plan view of the operating mechanism,

Figs. 7, 8, and 9, like views of the same in different stages of operation,

Fig. 10, a partial section on line 10-10 55 of Fig. 9, and

Fig. 11, a plan view of the operating mechanism with the top plate removed.

Like reference characters indicate like parts throughout the views. 60

In the present and preferred embodiment of my invention a rectangular outer casing comprises a body section 15 and a cover section 16 connected by hinges 17. The cover has an opening 20 in which registers 65 a door 21 engaged by a hinge 22 to the remainder of the cover.

The base 24 of the body section has preferably hinges 25 at one end engaging a side wall of the section. Pins 26 and 27 in the 70 cover and base respectively are engageable with hooks 28 and 29 pivotally attached by pins 30 and 31 on a side wall opposite the first mentioned wall. A pin 34 in the door 21 is engageable by a hook 35 pivoted on a 75 pin 36 in the cover. A handle 38 is pivoted in attaching plates 39 in the front wall of the body. Fast to the side walls of the body section are cleats 41 resting upon which, or detachably engaged thereto by 80 screws or in any convenient manner, is a horizontal partition or mounting board 42 which constitutes for operative purposes a part of the body section.

Fast to the top of the partition 42 by 85 screws 44 or otherwise is the base 45 of an internally threaded hollow post 48 in which is a screw 49 whose head 50 loosely rests in an internal annular recess 51 in a sleeve 52 journaled on the post and provided with 90 a flange 53 resting on the base 45. Fast to the sleeve 52 is a gear 55. Rigid with the sleeve above the gear is a carrier comprising a circular plate or disk 57.

Fast to the top face of the disk are a 95 series of radially arranged guides 59, in this instance twelve in number, of T shaped cross section, comprising vertical walls 60 supporting flanges 61. The areas of the disk between the guides form seats 62 for 100 segmental shaped glass plates 63 provided with sensitized upper faces and which are slidably into their seats with their sides in contact with the guide walls 60 and over-

lapped by the flanges 61. For retaining the slides against accidental escape, if desired, are spring clips, in this instance twelve in number, disposed radially intermediate the guides. Each clip comprises a flat resilient arm 66 with its inner end face fastened by solder or otherwise to the under face of the disk, and having upon its outer end an upturned finger 67 adapted to normally abut against the end of an adjacent plate 63, and terminating in a lateral projection or finger piece 68. By downwardly pressing the piece 68 the plate may be inserted or withdrawn from its seat.

Fastened to the inner face of the cover section by screws 70 or otherwise is a plate 71 provided with a segmental opening 72 bounded by a segmental flange 74. The opening 72 is of the shape and dimensions of a seat 62, and the depth of the flange is such that when the cover section is closed the edge of the flange is in slidable contact with or adjacent to the flange 61.

Depending from the board 42 is a frame 76 comprising an upper plate 77 and a lower plate 78 connected by corner posts 79. Upon the plate 77 are attaching lugs 80 with holes 81 to receive screws 82 which engage the frame with the under face of the board. In this instance the frame is inclosed by a cylindrical housing 83 having a closed bottom and open top attached to the frame or board in any convenient manner. Herein an in-turned intermittent flange 84 upon the top of the side wall 85 of the housing is slidably engaged by the heads of screws 87 annularly disposed in the board 42. Journaled in the plates of the frame 76 is an operating shaft 89 extending through a hole 90 in the board, fast to the upper end of which is a pinion 91 meshing with the gear 55. Through this shaft the carrier 57 is rotated step by step one twelfth of a revolution at the end of each and every hour. Each complete revolution of the shaft 89 advances the carrier disk one step.

The mechanism for operating this shaft may be of any construction best adapted for imparting thereto a revolution at the end of a determinate period, in this instance one hour. The form of operating mechanism herein shown consists of a special clock work mechanism, comprising a timing train or clock train having a key stem 93 journaled in the plates carrying the spring 94 and driving gear 95. 96 is the hour shaft, and 97 the escapement shaft mounted in the plates and carrying the escapement wheel 98. Stems 96 and 97 are rotated from shaft 93 by suitable intermediate gearing. The gear 95 engages lantern wheel 100 on shaft 96. Gear 101 on the latter engages lantern wheel 102 fast to a shaft 103 carrying gear 105. The latter engages a lantern wheel 107 on

shaft 108 carrying gear 109. The latter engages lantern wheel 110 on the shaft 97. The balance wheel 112 on a shaft 113 in the frames carries a balance spring 114 and is operatively connected with the wheel 98 through pin 115 engaging the lever 116 fast to shaft 117, and through pallet 118 fast to said shaft, as usual in timing mechanisms.

The shaft 89 is directly driven through a gear train including a key shaft 120 and operating spring 121. The shaft 120 carries a gear 122 engaging a lantern wheel 123 on shaft 124. The latter carries a pinion 125 meshing with a pinion 127 fast to shaft 89. In order to prevent racing of the shaft 89 a pallet 128 fast to a shaft 129 engages the teeth of a wheel 131 on shaft 124. Fast to the shaft 129 is a counter-weight 133.

The shaft 89 is governed by the hour shaft 96 by the following controlling device. Each of the screws or pins 135 and 136 in the plate 77 have washers or spacing pieces 139, 140, and 141. Upon the washers 139, resting directly on the plate, is a locking or controller plate 142 having oblong longitudinal slots 143 to loosely receive the screws. This plate 90 has upon one side three lateral fingers 144, 145, and 146. The finger 145 has a lateral shoulder 147. Another locking or controller plate 148 rests upon the washers 140 above the plate 142 and has oblong longitudinal 95 slots 149 to loosely receive the screws. This plate has a lateral finger 150 provided with an enlarged rectangular head or end portion 151 forming opposite shoulders 152 and 153. The washers 141 rest on this plate beneath 100 the heads of the screws 135 and 136. Both plates are longitudinally reciprocable by cams. Upon the shaft 89 is a cam 155 in the form of a sleeve with a lateral longitudinally disposed beak 156 engageable with the shoulders 147 and 152. The shaft 96 carries a cam 158 engageable solely with the finger 146. Above this is a second cam 160 upon the same shaft. This cam has an angular recess 161 in its periphery forming a rounded 110 shoulder 162 and a plane shoulder 163.

The operation of the controlling device is as follows: The carrier 57 has completed an advance, after which the parts are as shown in Fig. 7. The beak 156 of the cam 155 115 presses down against the shoulder 147 of the lower plate, and the shoulder 163 of the cam 160 engages the shoulder 153 of the upper plate. As the latter cam, which makes a complete revolution in one hour, 120 moves to the position shown in Fig. 8 the shoulder 162 forces the upper plate to the left bringing the shoulder 152 beneath the beak 156. In Fig. 9 the cam 158 has by its engagement with the finger 146 forced the shoulder 147 out of engagement with the beak 156 allowing the beak to come into engagement with the shoulder 152. The

plates retain the positions shown during nearly the whole of the remainder of the revolution of the cam 160. In Fig. 6 is shown the position of the parts at this instant. At all times the finger 150 or its head 151 is being forced against the cam 160 by a contractile spring 165 attached at one end to a screw 167 in an intermediate portion of the plate 148, and at its other end to the screw 136. The instant the cam completes its revolution, passing from the position shown in Fig. 6 to that in Fig. 7 the spring forces the plate 148 to the right and releases the cam beak 156, whereupon 15 the shaft 89 is instantaneously completely revolved by the spring 121 in the direction of the arrow and again rests on the shoulder 147.

During the described instant revolution of the shaft 89, its beak contacted with the finger 144 and returned the plate 142 to the position which it occupied prior to the action of the cam 158 thereon. This revolution of shaft 89 rotates the carrier 57 at the end of 25 the hour to a position one twelfth in advance of its original position. It will be noted that the described shift of positions involves no appreciable time, which is an important desideratum and fulfills one of the purposes 30 declared in the preamble.

I claim:—

1. In a spore trap, a casing, a disk rotatably mounted in the casing provided with radially disposed seats, said casing being 35 provided with an exposure opening above the seats, and means for rotating the disk.

2. In a spore trap, a casing, a disk rotatably mounted in the casing, radially disposed guides on the disk, and means for 40 rotating the disk.

3. In a spore trap, a rotatable disk, radially disposed guides on the disk, clips on the margin of the disk between the guides, and means for rotating the disk.

45 4. In a spore trap, a rotatable disk, radially disposed guides on the disk, sensitized plates slidably mounted on the disk between the guides, and means for rotating the disk.

50 5. In a spore trap, a casing, a disk rotatably mounted in the casing, radial guides on the disk, said casing being provided with an exposure opening above the disk, a flange in the casing bounding the opening adapted to register with two adjacent guides, and 55 means for rotating the disk.

60 6. In a spore trap, a casing comprising a body, a top cover provided with an exposure opening, a cover for the opening mounted on the first cover, and a horizontal partition in the body, a disk rotatably mounted on the partition provided with radially disposed seats movable in alignment with the opening, and means for rotating the disk.

7. In a spore trap, a casing comprising a

body, a top cover provided with an exposure 65 opening, a bottom cover, and a partition in the body, a carrier disk rotatably supported on the partition below the opening, and mechanism for driving the disk fast to the bottom of the partition.

70 8. In a spore trap, a casing provided with an exposure opening, a disk rotatably mounted in the casing below the opening, radially disposed seats on the disk adapted to successive register with the opening, and means 75 for intermittently rotating the disk.

9. In a spore trap, a casing provided with an exposure opening, a partition in the casing, a shaft rotatably supported on the casing, a carrier disk fast to the shaft below the 80 exposure opening, a gear fast to the shaft, a frame fast to the partition, an operating shaft journaled in the frame, a pinion on the operating shaft meshing with the gear, and mechanism in the frame for driving the operating shaft.

10. In a spore trap, a casing provided with an exposure opening, a partition in the casing, a post on the partition, a tubular shaft loose on the post, a carrier disk fast to the 90 shaft movable transversely of the opening, a gear on the shaft, a frame on the partition, an operating shaft mounted in the frame, a pinion on the operating shaft engaging the gear, and mechanism in the frame for imparting step by step movement to the operating shaft.

11. In a spore trap, a rotatable carrier disk, mechanism operable to impart continuous movement to said carrier, and means automatically operable to intermittently stop the carrier driving action of said mechanism.

100 12. In a spore trap, a rotatable carrier disk, mechanism operable to impart continuous movement to said carrier, and timed means for intermittently checking the driving action of said mechanism.

105 13. In a spore trap, a rotatable disk, an operating shaft therefor, gear mechanism operable to drive the shaft, an hour shaft, gear mechanism operable to drive the hour shaft, a stop cam on the first shaft, a cam on the second shaft, and reciprocable locking plates actuated by the second cam for engaging the stop cam.

115 14. In a spore trap, a rotatable carrier disk, twelve radial seats on the disk, an operating shaft for actuating the disk, a gear mechanism operable to drive the shaft, 120 a clock train including an hour shaft, and means actuated by the hour shaft for locking the operating shaft during a complete revolution of the hour shaft and then releasing the operating shaft.

125 15. In a spore trap, a rotatable carrier disk, an operating shaft therefor, a gear train including a spring operable to drive

the shaft, a cam beak carried by the shaft, a clock train mechanism including an hour shaft, a cam provided with an acute recess on the hour shaft, a second cam on the hour shaft, a reciprocable locking plate adapted to engage and release the beak, and engage the recessed cam, a retractile spring for maintaining said plate in constant engagement

with the recessed cam, and a second reciprocable locking plate actuated in one direction by contact with the beak, and moved in the other direction by contact with the second cam on the hour shaft. 10

In testimony whereof I have affixed my signature.

JOSEPH O. FULLER.
